ROLLER-CLUTCH.

No. 897,846.

Specification of Letters Patent.

Patented Sept. 1, 1908.

Application filed May 31, 1907. Serial No. 376,493.

To all whom it may concern:

Be it known that I, WILBUR J. OLDS, a citizen of the United States, residing in the city and county of Denver and State of Colorado, have invented certain new and useful Improvements in Roller-Clutches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in clutch mechanism more especially adapted for use in connection with ore feeders, in which the ore plate is intermittently actuated by the application of power to its shaft 20 which usually stands at a slight inclination to the vertical.

The object of my improved mechanism, is to provide a clutch or ratchet construction in which there shall be no lost motion. As 25 heretofore constructed so far as I am aware where the ordinary ratchet mechanism is employed whether in the form of balls acting in recesses having inclined walls, or whether the ordinary ratchet and pawl construction 30 is employed, there is always more or less lost motion, since the pawls usually fall away from the offset of the ratchet teeth as soon as the driving device ceases to act; while the balls roll backwardly out of direct engagement 35 with the walls of the driving and driven devices. These disadvantages or imperfections in the constructions noted, are more conspicuous, in constructions where the driven shaft occupies a vertical or an approxi- 40 mately vertical position, since in this event the movable parts of the ratchet mechanism are not assisted by gravity; and it is this class of devices to which my improved mechanism is more especially applicable.

45 In my improved construction, the driven shaft is provided with a disk having recesses formed in its periphery, the said recesses being closed on the outside by the depending flange of a driving device made fast to the 50 driving shaft. In these recesses are located rollers whose axes are parallel with the driven shaft. Seated in recesses adjacent those in which the rollers are located and communicating therewith, are coil springs which act

on the curved surfaces of the rollers about 55 midway of their longitudinal axes, whereby the said rollers are always held in positive contact with the walls of the recesses in which they are located one of the said walls being on the disk of the driven shaft while the 60 other is on the flange of the driving shaft as heretofore explained.

Having briefly outlined my improved construction, I will proceed to describe the same in detail, reference being made to the accompanying drawing in which is illustrated an embodiment thereof.

In this drawing, Figure 1 is a section taken through my improved mechanism just above the driven disk a portion of which is broken 70 away and sectionized to illustrate the seat for a coil spring. This section is taken approximately on the line 1—1 Fig. 2. Fig. 2 is a section taken on the line 2—2 of Fig. 1, the driven shaft, however, being shown in 75 elevation.

The same reference characters indicate the same parts in both views.

Let the numeral 5 designate the driving shaft to which is made fast a disk having a 80 flange or rim 7 extending at right angles to the body of the disk, the said flange being concentric to the axes of the shaft. The flange 7 surrounds a disk 8 to which is made fast the driven shaft 9 which may be con- 85 sidered the shaft of an ore feeder. In this event a disk (not shown) will be attached to the lower extremity of the shaft in a manner that will be readily understood.

Within the outer edge or periphery of the 90 disk 8 are formed recesses 10 which are closed on the outside by the inner surface of the driving flange 7. The inner walls of these recesses are curved as shown at 12, whereby the recesses diminish in width as 95 they extend forwardly or in the direction in which the disk moves, this direction being indicated by arrow A in Fig. 1. Within the recesses 10 are located cylindrical rollers 13 whose axes are parallel with the axes of the 100 shafts 5 and 9, the last named axes being in alinement in the construction shown in the drawing. As illustrated in the drawing three recesses 10 are formed. There may of course be any desired number of these recesses, preferably there should be at least three, to avoid any lateral thrust on the driven shaft in applying the power. By having three of

the roller devices, the pressure around the driven shaft incident to the action of the driving flange 7, is practically balanced which is an important feature in constructions of this class. The recesses 10 are formed entirely through the disk 8 and are closed at the bottom by a collar 14 which is fast on the shaft 9 and fits closely against the bottom of the disk 8. Formed in the disk 8 and communicating with the larger extremities of the recesses 10, are chambers 15 in which are located coil springs 16 acting on the rollers 13 about midway of their length (see Fig. 2). The tension of these springs is such as to hold the actuating rollers 13 in positive contact with the opposite walls of the recesses 10 at all times. Hence whenever the movement of the driving flange 7 ceases, the rollers 13 are still held in positive engagement with the said walls and ready to immediately impart motion to the disk 8 and the shaft 9, the instant the flange 7 begins its movement.

As shown in the drawing the disk 8 is connected with the shaft 9 by a key 17, whereby the disk and shaft are caused to rotate in unison.

From the foregoing description the use and operation of my improved mechanism will be readily understood. Every time a partial rotary movement is imparted to the shaft 5, the flange 7 of the actuating disk, acts on the rollers 13 to impart a corresponding partial

rotation to the disk 8, the shaft 9 and their connections.

Having thus described my invention, what I claim is:

In roller clutch mechanism, the combination with a driven disk and a driving member surrounding the disk, a collar keyed upon the driven shaft and engaging one surface of the driven disk, said disk and driving member being keyed to the driven and driving shafts respectively, the disk being provided with recesses closed on the outside by the driving member, the said recesses diminishing in width as they extend forwardly, rollers located in said recesses and having their axes parallel with the axis of the disk and extending through the said disk so as to engage the driving member at one extremity and the collar mounted upon the driven shaft at the other extremity, chambers formed in the said disk intermediate its surfaces and communicating with the wider extremities of the said recesses, and coil springs located in said chambers and acting on the rollers approximately midway of their length, substantially as described.

In testimony whereof I affix my signature in presence of two witnesses.

WILBUR J. OLDS.
